UNITED STATES PATENT OFFICE.

HUIE M. RASLEY, OF LETTS, IOWA.

ANTIRATTLING THILL-COUPING.

SPECIFICATION forming part of Letters Patent No. 629,172, dated July 18, 1899.

Application filed May 27, 1899. Serial No. 718,471. (No model.)

To all whom it may concern:

Be it known that I, HUIE M. RASLEY, a citizen of the United States of America, residing at Letts, in the county of Louisa and State of Iowa, have invented certain new and useful Improvements in Antirattling Thill-Couplings, of which the following is a specification, reference being had therein to the accompanying drawings.

This invention relates to antirattler attachments for thill-couplings, which can be used on those couplings now in general use of ordinary construction.

The object of the invention is to produce a novel form of spring for exerting pressure on the thill and to afford a novel means for retaining the spring and holding it in contact with said thill.

A further object of the invention is to produce an antirattling attachment which will possess advantages in points of simplicity, durability, and efficiency and prove at the same time comparatively inexpensive.

With the above and other objects in view the invention consists in the details of construction and in the arrangement and combination of parts to be hereinafter more fully set forth and specifically claimed.

In describing the invention in detail reference will be had to the accompanying drawings, forming part of this specification, wherein like characters denote corresponding parts in the several views, and in which—

Figure 1 is a side view of a thill-coupling attached to a vehicle-axle with the invention attached. Fig. 2 is a plan view looking at the bottom of Fig. 2. Fig. 3 is a perspective view illustrating certain elements of the invention detached.

In the drawings, 1 indicates the axle, 2 the clip, and 3 lugs of the clip that embrace the ends of the thill-socket, all of which being of usual and well-known construction will not be described in detail.

In connection with the thill and the apertured lugs it is my purpose to employ a bolt 4, having neither head nor threads, but having an annular groove 5 at each end. The bolts 4 are of such length as to project from each side of the lugs, and the grooves are so

positioned as to lie just outside the walls of said lugs. The thill-iron 6 has the usual socket or aperture to receive the bolt.

The antirattling device comprises a spring bent centrally with a looped portion 8 and parallel legs 9. Each leg is coiled around a yoke 10 near its ends, and the extremities 11 of the legs are bent up and curved to approximate the contour of the outer surface of the thill-sockets, which they engage. The yoke 60 has ends extending diagonally upward, with eyes 11^a formed by curving the said ends, and the eyes so formed receive the ends of the bolts which protrude through the lugs of the clip. The wire forming the eyes of the 65 ends of the yoke is partially embedded in the annular grooves, and as the spring exerts a downward pull on the yoke the ends are held in the grooves, and as the grooves, as described, are close to the walls of the lugs the 70 purpose is to have the loops forming the eyes of the yoke engage the sides of the lugs to further retain the parts in proper position. It will be noted, too, that the tension of the 75 spring presses the thill into firm engagement with the bolt and the bolt is held securely in the lugs. Hence the parts are not free to move or make a noise.

As a means for regulating the tension of the spring a loop 12 is arranged over the clip-plate 13 and has its ends 14 attached to the legs of the spring by being coiled therearound. When the loop is applied, the tension of the 80 spring may be varied according to the length of the loop, and should the spring become 85 weak a shorter loop may be readily applied without the exercise of undue skill.

The construction, operation, and advantages will, it is thought, be understood from the foregoing description, and it will be noted that the proportions may be varied in order to successfully carry the invention into practice, as will be obvious to those skilled in the art.

Having fully described the invention, what 95 I claim as new, and desire to secure by Letters Patent, is—

In an antirattling attachment for thill-couplings, the combination of the thill, the lugs, a bolt run through apertures of the lugs 100

and thill, and having annular grooves in each end just clearing the sides of the lugs, a yoke having a curved end lying in the grooves and engaging the sides of the lugs, a spring bent centrally and having its legs coiled around the yoke with its extremities bent up and curved to engage the thill, the said spring extending rearwardly, and a loop extending over a clip-plate and having its ends coiled

around the legs of the spring, as and for the purpose described.

In testimony whereof I affix my signature in the presence of two witnesses.

HUIE M. RASLEY.
